UNITED STATES PATENT OFFICE

FRANZ THOMA, OF KAAN-MARIENBORN, GERMANY

WORK REST FOR MATERIAL REDUCING MACHINES

Application filed February 11, 1931, Serial No. 515,087, and in Germany January 18, 1930.

The invention relates to work rests used for supporting heavy pieces of work such as rolls in material reducing machines. Such rests are used for accurate work in lathes, 5 grinder and like machines adapted to reduce the diameter of the piece of work.

The usual method of setting up the work is to support it between centers; for particularly accurate results dead centers are used, 10 i. e. such as do not participate in the rotation of the work. The centers are then relieved as far as possible of the weight of the work by placing supports of some kind under the work contacting with it by bearing saddles or rollers.

It has hitherto been usual to adjust the pressure exerted by such supports or work rests simply by feeling and then to clamp the adjustment fast so that the distance of the 15 rest from the machine center was invariable.

It occurs in some cases that the part of the work engaged by the rest is not accurately round and so the pressure taken up by the rest varies during the rotation of the work. 20

Thus the thrust on the center is continually varying in the course of one rotation and center holes are worked into the piece of work with axes displaced from the original axis; in 25 other words the centers run out of line.

The object of the present invention is to 30 overcome this drawback. According to the invention the work is supported in combination with the centering devices by one or

more intermediate yieldable supports urged 35 against the work with a predetermined pressure. Preferably the pressure means is such as to give nearly constant pressure throughout the useful range of movement. This

may be accomplished by weights, springs or 40 other suitable means. Usually the pressure means is adjustable to suit different pieces of work; in general the pressure is adjusted to the value it would have if no support at all were afforded by the centers. In the case 45 of a symmetrical arrangement with two supports the value would thus be half the weight of the work on each of them.

If a saddle bearing with sliding contact is 50 used it should preferably be movable in all directions or by being placed on a spherical

seating, so that it may contact well with the work at every position. I prefer, however, to use as supporting structure two rollers placed respectively in front of and behind the vertical plane through the centers, in the 55 simplest case equidistant from this plane, and to press the rollers against the work with forces which are in equilibrium with the proportion of the weight acting at the point of support. These rollers are preferably journaled in levers having their fulcrums in the body of the rest. While the levers associated with the front and back rollers may be independently pivoted and loaded I prefer to pivot both levers in the vertical plane passing 60 through the centers and to connect the outer ends of the levers by an adjustable spring thus providing a scissors movement.

Further features of the invention will be described in conjunction with the accompanying drawings, in which:—

Figure 1 is a diagrammatic elevation of a grinder with a mill roll in place supported by weight loaded work rests according to the invention, but omitting the grinding and 75 driving mechanisms for sake of clarity.

Figure 2 is a cross section through II—II of Figure 1 but on a larger scale.

Figure 3 is a view similar to Figure 2 of a modification showing a spring loaded rest 80 with rollers, and

Figure 4 is a plan, partly in section, of the rest of Figure 3.

Referring to Figure 1 the bed of a grinder is shown at 1 on which the heads 2 carrying the dead centers 3 are mounted in the usual manner. A mill roll 4 is shown mounted on the centers and is adapted to be rotated by any suitable means (not shown) preferably by a belt of conical cross section. The roll 85 journals are shown at 5 and it is at these parts that the work is supported by the rests forming the subject-matter of the invention. The reference numerals 6 and 7 represent the left and right hand work rests as a whole. 90

The construction of the rests is shown in Figure 2. In this Figure 8 is the base plate sliding in the usual way on the machine bed 1 and located transversely by a V-guide 31. The usual fixing bolts (not shown) engage 100

the T-grooves 32. From the base plate 8 a fixed arm 9 projects forwards and upwards and the base plate also carries a pin or shaft 10 slightly in front of the vertical center plane of the machine forming a fulcrum for the lever 11. The shorter or rear arm of this lever has on its upper face a spherical seating 12 accommodating the spherical face 13 of a bearing saddle 14 shaped to fit the journal 5. It will be noted that the arc of contact of the bearing saddle 14 is a comparatively small part of the circumference of the journal 5, so that the greater part of the latter is available for the access of the grinder and for the necessary cooling, which latter is of very great importance in accurate work. The longer or front arm of the lever 11 is connected at its end 33 by a link 15 to a lever 34 at a point 35 between its fulcrum 36 on the arm 9 and its outer end. At the outer end 37 of the lever 34 a rod 38 is suspended for the reception of disc weights 16. Any desired number of weights 16 may be put into place so as to counterbalance through the lever system the proportion of the weight of the roll to be borne by the saddle 14. As stated above this is usually half the weight of the roll, two similar rests being provided at the positions 6 and 7 of Figure 1.

An alternative construction is shown in Figures 3 and 4. The base plate 8 of the rest is supported as before and carries in the center plane of the machine a bearing pin or shaft 17 parallel to the machine axis. Two levers 18 are pivoted on the shaft 17 and are connected together at their shorter rear ends by a shaft 19 and at their longer front ends by a rotatable distance piece 20. The shaft 19 carries by means of roller bearings 21 a roller 22. Discs 23 fast on the shaft 19 are shaped to form with the sides of the roller 22 a labyrinth packing for the inside of the roller, so that one lubrication of the roller lasts a very long time. Between the levers 18 and also on the shaft 17 there are pivoted two other levers 24 connected at their outer ends by a rotatable distance piece 25 and by a shaft 26 at a distance from the pivot 17 equal to the distance of the shaft 19 therefrom but in the opposite direction. The shaft 26 carries a roller 27 precisely similar to the roller 22. The front or outer ends of the levers 18 are bent obliquely upwards, and those of the lever 24 obliquely downwards; also the ratio of leverage is the same in both, so that the distance piece 20 is a certain distance vertically above 25.

Through holes in the distance pieces a rod 28 is passed. A spiral spring 29 threaded on the rod 28 bears at the one end against the distance piece 25 and at the other against the nut 30 screwed on to the rod. The upper end of the rod is provided with a long screw thread 39 on which the hand wheel 40 with tapped bore forms a nut. This hand wheel

presses on distance piece 20 as it is screwed down.

The operation of the rest is as follows. The roll is mounted between the centers of the grinder, then the hand wheel 40 is screwed down until the rollers 22 and 27 come into contact with the roll journals 5. The spring 29 remains up to this moment practically without strain. The other work rest is similarly set. Then the handwheels 40 of both are turned, still further tensioning the spring 29 until the rollers 22 and 27 press upwards with the desired force against the roll journals 5 and thus relieve the centers 3 of all weight.

If the center line of the work retains its position unchanged between the centers, as is intended, and one or both journals are not true, it will be seen that the rollers 22 and 27 move up and down as the radius from the center line to the point of contact of the roller on the journal varies. This movement is transmitted in increased value to the distance piece, so that the spring 29 is subjected at each rotation of the work to a slightly varying strain so long as the journals run out of line. As such pieces of work are only set on precision machines after accurate preliminary work, the lack of accuracy of the journals is of course very slight, and the properties of the spring 29 are so selected that the force with which the rollers are pressed on to the work remains practically constant in spite of the variation in spring tension. When in the course of the fine grinding the journals have become quite true, the oscillations of the spring 29 in the construction of Figures 3 and 4 and of the rod 38 in the construction of Figure 2 cease, so that a reliable signal is provided indicating the progress of the work.

Clearly the mechanism serving to press the saddle, rollers, or other supporting members against the work must not be self-locking, i. e. such as to be capable of movement in one direction only, but it must on the contrary be reversible in that the supporting members can rise and fall exerting substantially the same pressure in both cases. Further there must be no stop for the innermost working position, that is the position nearest the center line of the work; on the other hand the rest in this position, which it reaches when the journal is down to correct size, must still exert the predetermined pressure on the work.

I claim:

Means for supporting heavy pieces of work in material reducing machines comprising in combination with centering devices two work supporting rollers located one on either side of the vertical plane through the axis of rotation of the work and mounted on pairs of levers fulcrumed substantially in the said plane, the longer arms of the levers projecting towards the same side of the machine, one pair obliquely upwards and the other pair 135

obliquely downwards, and a tension rod with a nut bearing on a distance piece connecting the ends of the arms of one lever pair and a nut bearing in the opposite direction through 5 a spring on a distance piece connecting the ends of the arms of the other lever pair, giving a scissors movement of the levers.

In testimony whereof I affix my signature.
FRANZ THOMA.
